COLD GAS CARBURETOR AND GENERATOR

Gene P. Hurlburt, Los Angeles, Calif., assignor
to Maxwell C. Knowles, Los Angeles, Calif.

Application July 2, 1935, Serial No. 29,484

16 Claims. (Cl. 261—88)

My invention relates to a carburetor, and gas generator for generating gas from hydrocarbon fluids, such as gasoline, distillate, Diesel oil, alcohol and other like fluids, without in any way heating or raising the temperature of the fluid during the treatment, and the objects of my invention are:

First, to provide a carburetor and gas generator of this class in which the fuels are completely broken up and atomized in a partial vacuum by means of velocity and impact before they are mixed with the air on its way to a point of combustion;

Second, to provide a carburetor and gas generator of this class in which the fuel mixture is automatically controlled relative to the air flow through the carburetor and generator regardless of the varying speeds or loads;

Third, to provide a carburetor and gas generator of this class in which the fuel and air mixture is in proper proportion regardless of elevation, pressure or temperature variations;

Fourth, to provide a carburetor and gas generator of this class in which the gas may be generated while it is absolutely cold until it reaches a point of combustion;

Fifth, to provide a carburetor and gas generator of this class in which the power derived from combustion of the gas generated thereby is a maximum in efficiency;

Sixth, to provide a carburetor and gas generator of this class in which an engine's efficiency is increased to a large degree over the conventional carburetors now in use;

Seventh, to provide a carburetor and gas generator of this class which reduces the carbon monoxide gas from combustion to a minimum; and

Eighth, to provide a carburetor and gas generator of this class which is simple and economical of construction, durable, efficient, easy to operate, simple to adjust, and which will not readily deteriorate or get out of order.

With these and other objects in view as will appear hereafter, my invention consists of certain novel features of construction and arrangement of parts and portions as will be hereinafter described in detail and particularly set forth in the appended claims, reference being had to the accompanying drawings and to the characters of reference thereon which form a part of this application, in which:

Figure 1 is a vertical sectional view along the line 1—1 of Fig. 2 of my carburetor and gas generator complete showing some of the parts and portions in elevation to facilitate the illustration;

Fig. 2 is a transverse sectional view along the line 2—2 of Fig. 1; Fig. 3 a transverse sectional view on an enlarged scale along the line 3—3 of Fig. 1, and Fig. 4 a fragmentary sectional view along the line 4—4 of Fig. 3.

Similar characters of reference refer to similar parts and portions throughout the several views of the drawings.

The casing members 1 and 2, inlet bracket 3, fuel nozzle 4, spiral turbine 5, rotor 6, fuel distributor spiral 7, fuel distributor radiating members 8, and butterfly valve 9, constitute the principal parts and portions of my cold gas carburetor.

The casing member 1 is a shell like casing provided with a reduced intermediate straight portion 1a with an upper enlarged portion 1b and a lower enlarged portion 1c, and the lower end of the enlarged portion 1c is provided with an outwardly extending annular flange 1d which is provided with a plurality of perforations adapted to receive the bolts 1e. Mounted in the upper edge of the upper enlarged portion 1b is the air and fuel inlet bracket 3 which is supported in the end of said casing 1 by means of screws 3a. This bracket 3 is substantially spider in form provided with a rim portion 3b, a central portion 3c, and connecting members 3d. One of the connecting members, designated 3e, is enlarged and raised relatively to the other members and serves as the inlet 3f for the fuel which comes from any source and is controlled by a fuel control valve before it reaches the conductor portion 3f in the inlet bracket 3. This bracket is provided with a screw threaded portion 3g adapted to receive a connection for the fuel conductor. The conductor portion 3f is enlarged in its vertical portion in which is secured a nozzle member 4 preferably by force fit, and this nozzle member extends downwardly below the lower surface of the member 3 some distance, as shown best in Fig. 1 of the drawings.

Secured in the lower end of the casing member 1 in the enlarged portion 1c is the casing member 2 which is provided with an upwardly extending annular portion 2a which has a corrugated or channelled inner surface 2b, shown best in Figs. 1 and 3 of the drawings, which consists of alternate ridges and grooves adapted to assist in the mixing of the fuel and intermixing it with the air as will be hereinafter described. This portion 2a is provided with an outwardly extending annular flange 2c which is adapted to fit against the flange 1d and these flanges are secured rigidly together by means of the bolts 1e. This casing

member is provided with an inwardly and downwardly diverging wall 2d and with a vertical opening 2e for conducting the fuel mixture of air and gas to the intake manifold of the gas engine or for other use. The lower end of this portion 2e is provided with a flange 2f to facilitate its securing to the intake manifold of a gas engine or to a like conductor to any point of combustion.

10 Mounted in the fuel outlet portion 2e is a conventional butterfly valve 9 which is controlled from the outside in the conventional manner for regulating the flow of fuel to the point of combustion.

Secured at the juncture of the portions 2d and 15 2e of the casing member 2 are leg members 2g which extend upwardly and inwardly and support at their upper end a ball bearing cage 2h, all as shown best in Fig. 1 of the drawings. Mounted in this cage 2h is a ball bearing 6a 20 which forms the bearing for the rotor member 6, the rotor member 6 being provided with a downwardly extending annular lug portion 6b mounted within the roller bearing 6a. The rotor member 6 is a hollow cup-shaped member in 25 which is mounted a fuel distributor spiral 7, the lower edge of which is mounted in a spiral groove 6c which spiral starts near the center of the rotor 6 and extends in spiral form outwardly and terminates against the inner side wall of the rotor 6 at point 7a and the side wall of the rotor 6 is provided with small outlet orifices 6d, shown 30 best in Fig. 4 of the drawings, for thrusting the atomized fuel gas against the corrugated surface 2b of the casing member 2 in the rotation of said rotor member. This spiral is divided by a 35 plurality of radiating partitions 8 which extend between the different coils of the spiral and each of these radiating members 8 is provided with a plurality of small orifices through which the fuel 40 or liquid must pass as it follows the spiral from the central portion outwardly with the revolution of the rotor.

Mounted on the upper side of the rotor 6 is a cover 6g which is provided with a central opening 6e for directing the fuel or liquid to the central portion of the rotor. This cover member 6g is provided with an upwardly extending lug portion centrally therein 6f in which is secured preferably by force fit the lower end of the spiral turbine 5. This spiral turbine 5 consists of an axle member 5a which is provided with a central longitudinal orifice 5b which serves as a conductor for the fuel or liquid and communicates at its upper end with the nozzle 4. Mounted on this 55 axle 5a is a spiral 5c which is secured thereto and extends practically a full circle around the axle 5a and fits in the portion 1a of the casing 1 leaving slight clearance at the periphery of the spiral 5c, as shown best in Fig. 1 of the drawings. The axle 5a is reduced at its upper end at 60 5d and is supported in ball bearings 5e mounted in a recess in the bracket 3 and surrounding the nozzle 4.

65 The operation of my carburetor and generator is as follows: Fuel or liquid is admitted to the carburetor through the orifice 3f from any source of supply and regulated by a valve in the conventional manner. Air is admitted through the openings 3h in the bracket 3 and passes downwardly into the casing 1 operated by the vacuum to the intake manifold or other conductor to a point of combustion. This air engages the spiral 5c causing the same to rotate depending upon the flow of the air. This in turn revolves the 70 75 axle 5a and rotor 6 through the rotor cover 6g.

The fuel or liquid pass through the conductor 3f, nozzle 4, through the axle 5a and into the central portion of the rotor 6 through the orifice 6e where it is taken up by the inner portion of the spiral 7 with the rotation of the rotor 6 and circulated outwardly by the spiral to the outer portion of the rotor and passes outwardly through the orifice 6d and against the corrugated portion of the wall of the casing member 2 as hereinbefore described; it being noted that the 10 fuel or liquid is broken up and atomized by passing through the orifices in the partitions 8 as well as the whirling motion caused by the spiral in its rotation. The whirling motion together with the construction of the spiral in the hermetically sealed rotor causes a partial vacuum in the rotor thus allowing the fuel or liquid to obtain its treatment without having any air intermixed and thereby permits greater breaking up before being mixed with the air stream. The 15 fuel or liquid is taken up by the air in its passage between the outer edge of the rotor 6 and the inner surface 2b of the casing 2 and carried downwardly past the butterfly valve 9 and thence to the point of combustion. 20 25

Though I have shown and described a particular construction and arrangement of parts and portions, I do not wish to be limited to this particular construction and arrangement but desire to include in the scope of my invention, the 30 construction and arrangement substantially as set forth in the appended claims.

Having thus described my invention, what I 35 claim as new and desire to secure by Letters Patent is:

1. In a cold gas carburetor and generator, a casing, a spiral turbine revolvably mounted therein, a fuel conduit extending from the upper side of said casing downwardly through the axis of said turbine, and a rotor of greater diameter than 40 said turbine operatively connected with said turbine in said casing arranged to receive and distribute fuel from the periphery of said rotor.

2. In a cold gas carburetor and generator, a casing, a spiral turbine revolvably mounted therein, a fuel conduit extending from the upper side of said casing downwardly through the axis of said turbine, a rotor of greater diameter than 45 said turbine operatively connected with said turbine in said casing arranged to receive and distribute fuel from the periphery of said rotor, and a fuel atomizing spiral mounted in said rotor with its central portion communicating with the fuel conduit.

3. In a cold gas carburetor and generator, a 55 casing, a spiral turbine revolvably mounted therein, a fuel conduit through the axis of said turbine, a rotor operatively connected with said turbine in said casing arranged to receive and distribute fuel from the periphery of said rotor, a 60 spiral mounted in said rotor with its central portion communicating with the fuel conduit, and perforate partitions positioned in said spiral from end to end thereof.

4. In a cold gas carburetor and generator, a 65 casing, a spiral turbine revolvably mounted therein, a fuel conduit extending from the upper side of said casing downwardly through the axis of said turbine, and a rotor of greater diameter than 70 said turbine operatively connected with said turbine in said casing arranged to receive and distribute fuel from the periphery of said rotor, said casing provided with a corrugated surface in close proximity to the outlet openings of said rotor. 75

5. In a cold gas carburetor and generator, a casing, a spiral turbine revolvably mounted therein, a fuel conduit extending from the upper side of said casing downwardly through the axis of said turbine, a rotor operatively connected with said turbine in said casing arranged to receive and distribute fuel from the periphery of said rotor, and a spiral mounted in said rotor with its central portion communicating with the fuel conduit, said casing provided with a corrugated surface in close proximity to the outlet opening of said rotor.
- 10 5. In a cold gas carburetor and generator, a casing, a spiral turbine revolvably mounted therein, a fuel conduit through the axis of said turbine, a rotor operatively connected with said turbine in said casing arranged to receive and distribute fuel from the periphery of said rotor, a spiral mounted in said rotor with its central portion communicating with the fuel conduit, and perforate partitions positioned in said spiral from end to end thereof, said casing provided with a corrugated surface in close proximity to the periphery of said rotor adapted to receive the fuel from said rotor for mixing the same.
- 15 6. In a cold gas carburetor and generator, a casing provided with an air conduit therethrough, a turbine mounted in said casing arranged to operate by the flow of air through said casing, a downwardly directed fuel conduit through said turbine, a bracket mounted in the upper inlet end of said casing provided with both air and fuel conduits therein, a fuel nozzle secured in said bracket and arranged to conduct fuel into said turbine conduit, a fuel distributing rotor of greater diameter than said turbine mounted in said casing in secured relation with said turbine.
- 20 7. In a cold gas carburetor and generator, a casing provided with a downwardly directed air conduit therethrough, a turbine mounted in said casing arranged to operate by the flow of air through said casing, a downwardly directed fuel conduit through said turbine, a bracket mounted in the upper inlet end of said casing provided with both air and fuel conduits therein, a fuel nozzle secured in said bracket and arranged to conduct fuel into said turbine conduit, a fuel distributing rotor mounted in said casing in secured relation with said turbine.
- 25 8. In a cold gas carburetor and generator, a casing provided with a downwardly directed air conduit therethrough, a turbine mounted in said casing arranged to operate by the flow of air through said casing, a downwardly directed fuel conduit through said turbine, a bracket mounted in the upper inlet end of said casing provided with both air and fuel conduits therein, a fuel nozzle secured in said bracket and arranged to conduct fuel into said turbine conduit, a fuel distributing rotor mounted in said casing in secured relation with said turbine, said rotor partitioned with a fuel atomizing spiral with its one end positioned substantially centrally of said rotor and extending outwardly to the outer side thereof.
- 30 9. In a cold gas carburetor or generator, a casing provided with an air conduit therethrough, a turbine mounted in said casing arranged to operate by the flow of air through said casing, a fuel conduit through said turbine, a bracket mounted in the inlet end of said casing provided with both air and fuel conduits therein, a fuel nozzle secured in said bracket and arranged to conduct fuel into said turbine conduit, a fuel distributing rotor mounted in said casing in secured relation with said turbine, said rotor partitioned with a spiral with its one end positioned substantially centrally of said rotor and extending outwardly to the outer side thereof, a plurality of perforate partitions positioned throughout said spiral, and fuel outlet openings through the periphery of said rotor.
- 35 10. In a cold gas carburetor or generator, a casing provided with an air conduit therethrough, a turbine mounted in said casing arranged to operate by the flow of air through said casing, a fuel conduit through said turbine, a bracket mounted in the inlet end of said casing provided with both air and fuel conduits therein, a fuel nozzle secured in said bracket and arranged to conduct fuel into said turbine conduit, a fuel distributing rotor mounted in said casing in secured relation with said turbine, said rotor partitioned with a spiral with its one end positioned substantially centrally of said rotor and extending outwardly to the outer side thereof, a plurality of perforate partitions positioned throughout said spiral, and fuel outlet openings through the periphery of said rotor.
- 40 11. In a cold gas carburetor and generator, a casing provided with an air conduit therethrough, a turbine mounted in said casing arranged to operate by the flow of air through said casing, a fuel conduit through said turbine, a bracket mounted in the inlet end of said casing provided with both air and fuel conduits therein, a fuel nozzle secured in said bracket and arranged to conduct fuel into said turbine conduit, a fuel distributing rotor mounted in said casing in secured relation with said turbine, said rotor partitioned with a spiral with its one end positioned substantially centrally of said rotor and extending outwardly to the outer side thereof, a plurality of perforate partitions positioned throughout said spiral, and fuel outlet openings through the periphery of said rotor.
- 45 12. In a cold gas carburetor and generator, a spiral air operated turbine, a rotor operatively connected therewith, and a fuel atomizing means in said rotor, said fuel atomizing means consisting of a spiral having its fuel receiving end approximately centrally of said rotor and extending outwardly therefrom to the outer side of said rotor, and a plurality of perforate partitions positioned in said spiral.
- 50 13. In a cold gas carburetor and generator, a spiral air operated turbine, a rotor operatively connected therewith, a fuel atomizing means in said rotor, said fuel atomizing means consisting of a spiral having its fuel receiving end approximately centrally of said rotor and extending outwardly therefrom to the outer side of said rotor, and a plurality of perforate partitions positioned in said spiral, a casing in which said turbine and rotor are revolvably mounted forming an air confining passage for said turbine.
- 55 14. In a cold gas carburetor and generator, a spiral air operated turbine, a rotor operatively connected therewith, a fuel atomizing means in said rotor, said fuel atomizing means consisting of a spiral having its fuel receiving end approximately centrally of said rotor and extending outwardly therefrom to the outer side of said rotor, and a plurality of perforate partitions positioned in said spiral, a casing in which said turbine and rotor are revolvably mounted forming an air confining passage for said turbine, said casing provided with a fuel spreading surface contiguous to the periphery of said rotor.
- 60 15. In a cold gas carburetor and generator, a spiral air operated turbine, a rotor operatively connected therewith, a fuel atomizing means in said rotor.

said rotor, said fuel atomizing means consisting of a spiral having its fuel receiving end approximately centrally of said rotor and extending outwardly therefrom to the outer side of said rotor, 5 and a plurality of perforate partitions positioned in said spiral, a casing in which said turbine and rotor are revolubly mounted forming an air confining passage for said turbine, said casing provided with a fuel spreading surface contiguous 10 to the periphery of said rotor, the space between said fuel spreading surface and the periphery of said rotor forming a restricted surface for the passage of air through said casing.

16. In a cold gas carburetor and generator, a

spiral air operated turbine, a rotor of greater diameter than said turbine operatively connected therewith, a fuel atomizing means in said rotor, said fuel atomizing means consisting of a fuel atomizing spiral having its fuel receiving end approximately centrally of said rotor and extending outwardly therefrom to the outer side of said rotor, and a hermetically sealed casing for 5 said rotor whereby a partial vacuum is created in said rotor preventing air cushioning of particles of the fuel, thus permitting greater breaking up of said fuel. 10

GENE P. HURLBURT.
